UNITED STATES PATENT OFFICE.

WILHELM EHMKE, OF MILWAUKEE, WISCONSIN.

COOLING-COIL FOR REFRIGERATOR-BOXES.

1,273,162.

Specification of Letters Patent. Patented July 23, 1918.

Application filed May 3, 1917. Serial No. 166,261.

To all whom it may concern:

Be it known that I, WILHELM EHMKE, a citizen of the United States, and resident of Milwaukee, in the county of Milwaukee 5 and State of Wisconsin, have invented certain new and useful Improvements in Cooling-Coils for Refrigerating-Boxes; and I do hereby declare that the following is a full, clear, and exact description thereof.

10 My invention relates to certain new and useful improvements in refrigerating or cooling boxes in which a brine or service water is employed as the cooling medium.

In a large number of the refrigerating boxes now in general use, the cooling coils are composed of a series of pipes running longitudinally or transversely in the box which is a very expensive arrangement, and with this inherent objection in view, my invention has for its primary object to provide a refrigerating box in which the coil is formed in two sections, each section being stamped from a single sheet of metal and then being secured together as will be hereinafter described.

20 A further object of my invention is to provide a refrigerating box in which the cooling coil will be composed of two sections, each stamped from a single sheet of 30 metal which, when placed together, will have formed therebetween a serpentine or tortuous passage for the cooling medium.

With the above and other minor objects in view, which will appear as description proceeds, my invention resides in the novel construction, arrangement, and combination of parts substantially as herein-after described and more particularly defined by the claim, it being understood that 40 changes in the precise embodiment of the invention herein disclosed may be made without departing from the spirit of the invention.

In the accompanying drawings I have 45 illustrated one complete example of the physical embodiment of my invention constructed according to the best mode I have so far devised for the practical application of the principles of my invention; in which,

50 Figure 1 is a sectional view through the refrigerating box, the coils thereof being shown in top plan view, and

Fig. 2 is a sectional view taken on the line 2—2 of Fig. 1.

55 My invention resides essentially in the manner of constructing the cooling or re-

frigerating coils which are disposed in the refrigerating box 5 including the side and rear walls 6, top and bottom 7, and front hinged door 8 all supported upon legs 9, 60 the said door, side and rear walls, and top and bottom having on the inner portion thereof any suitable non-heat conducting material 10 such as mineral wool, cork, or the like. This material adjacent the top 65 and bottom is held in position by a false top and bottom 7', and the door 8 has a false back 8' for the same purpose.

My coil forms an inner wall for the refrigerating box casing as it is spaced from 70 the side walls of the latter although it is in contact with the false top and bottom. Such an arrangement obviously prevents the mineral wool, cork or other finely divided insulating material from escaping and holds it 75 in operative position without the addition of the usual retaining wall. It comprises two like sections 11, each of which sections are struck from a single sheet of metal and bent to conform to the shape and size of the 80 box as shown in Fig. 1. These sections have the correspondingly raised portions 12 resembling the pipe coils now in general use, and when the two sections are secured together by the rivets or other fastenings 13, 85 the raised portions 12 of one section aline with those of the other section making a tortuous or serpentine passage way for the cooling means.

As a simple means for holding the coil 90 properly spaced from the side walls of the box, I provide the false top and bottom 7' with grooves which extend parallel to and are spaced from said side walls as shown at 20 to receive the upper and lower edges 21 95 of the sheets forming the coil. This eliminates the necessity for inserting fastening elements through the sheets, while at the same time it absolutely prevents the coil from springing away from the walls of the 100 box.

The coils, of course, being provided at one end with the inlet 14 and at the other extreme end with the outlet 15, the service water or brine, as the case may be, enters at 105 14 and describes a zigzag route through the passages 16 formed by the raised portions 12, in the manner as indicated by arrows in Fig. 2.

In most of the inventions of this character, when used with the service water, great difficulty has been encountered in construct-

ing one strong enough to withstand the pressure to which it is subjected when its outlet valve (not shown) is closed and its inlet valve (not shown) is open, which is 5 normally about forty pounds to a square inch. My construction eliminates this danger of the coils bulging or becoming leaky under strain of the pressure by reason of its strength and durability of construction, 10 and further it is of such simple construction as to be wholly desirable and practical.

I claim:

15 In a refrigerator having the side wall provided with a layer of finely divided non-heat conducting material, composite top and bottom sections fitted thereto, the inner face of said sections each having a groove paralleling the side wall and spaced therefrom a distance equal to the thickness of the layer 20 of said material, the combination of a metallic lining unit for the refrigerator side wall

comprising a sheet formed from a pair of unbroken plates, the same being complementarily stamped to provide longitudinally disposed channels communicating at 25 their upper and lower ends to form a continuous passage-way, said lining being longitudinally bent at intervals between said channels to conform to the contour of the refrigerator side wall, the top and bottom 30 edges of the plates forming the lining being brought together to constitute seam beads for disposition in said grooves of the top and bottom sections to secure said non-heat conducting material in position and to 35 hold said lining in spaced relation to the side wall.

In testimony that I claim the foregoing I have hereunto set my hand at Milwaukee, in the county of Milwaukee and State of Wisconsin.

WILHELM EHMKE.
